THOMAS TIBBETS, OF ELLICOTT CITY, MARYLAND, ASSIGNOR OF THREE-FOURTHS TO
JOHN C. TIBBETTS, OF ELLICOTT CITY, MARYLAND.

PROCESS AND APPARATUS FOR PRODUCING AND MAINTAINING A VACUUM.

1,427,656.

Specification of Letters Patent. Patented Aug. 29, 1922.

Application filed December 24, 1917. Serial No. 208,597.

To all whom it may concern:

Be it known that I, THOMAS TIBBETS, a citizen of the United States, and a resident of Ellicott City, in the county of Howard and State of Maryland, have invented a new and useful Improvement in Processes and Apparatus for Producing and Maintaining a Vacuum, of which the following is a specification.

10 My invention relates to improvements in process and apparatus for producing and maintaining a vacuum, and it consists in the steps hereinafter pointed out, and the means for accomplishing the same.

15 An object of my invention is to provide an improved process whereby a partial vacuum may be produced and maintained, and in which the necessity for mechanical devices such as pumps, condensers, etc. is 20 eliminated.

A further object of my invention is to provide a process which may be carried out with any ordinary boiler, by the addition of a U-shaped tube or pipe which may 25 be attached to the boiler or built in with it.

30 A further object of my invention is to provide a process for providing and maintaining a vacuum or reduction of pressure which requires no attention to keep the system in order.

Other objects and advantages will appear in the following specification, and the novel features of the invention will be particularly pointed out in the appended claims.

35 My invention is illustrated in the accompanying drawings forming a part of this application, in which:

Figure 1 is a section through a boiler constructed according to my invention, and

40 Figure 2 is a diagrammatic view of a steam heating system to which my improved process and apparatus are applicable.

My invention is applicable to any use in which a partial vacuum is desired. It 45 is particularly adapted for maintaining a vacuum in steam heating systems. I have, therefore described such a system to illustrate my invention.

In carrying out my invention I make 50 use of any suitable boiler. In the drawings this boiler is shown as having a base 1, an ash pit 2, a grate 3, a combustion chamber 4, an outlet 5 for exhaust gases, and a water jacket 6. Surmounting the water 55 jacket is a steam dome 7.

The parts mentioned thus far are to be found in ordinary types of boilers and constitute no part of the present invention except as they cooperate with the parts hereinafter described, to produce novel 60 results.

Connected with the bottom of the steam dome 7 is a downwardly extending pipe 8 which is connected by a laterally extending connection 9 with a vertically extending pipe 10. A pipe 11 communicates at 12 with the bottom of the water jacket 8, that is to say, with the bottom of the boiler, at one end, and at the other end with a pipe 13, this pipe 13 being the return pipe from 70 the radiators 14. The pipe 13, as will be observed, communicates with the pipe 10, a check valve 15 being interposed so that a rearward flow, that is to say, from the pipe 10 to the pipe 13 is prevented. The pipe 75 10 also communicates with the pipe 16 having a check valve 18 to prevent back flow into the pipe 10.

In Figure 2 I have shown a steam pipe 19 connected with the steam dome of the 80 boiler and leading to the radiators 14, these radiators being connected by the return pipe 13, in the manner shown.

From the foregoing description of the various parts of the device the operation 85 thereof may be readily understood.

Fire is started in the combustion chamber 4 in the usual manner and the heat from the fuel around tube 8 causes steam to form at that point in the tube, which rises through 90 it to the surface of the water in the steam dome 7. In rising it lifts a portion of the water in tube 8 with it, which causes the water in tubes 9 and 10 to be drawn after it and the surface of the water in tube 95 10 to fall. As soon as the steam escapes from the tube 8 the balancing of weight of the water in tubes 8, 9 and 10 causes water from the steam dome to be drawn into the tube 8 and the surface of the water in tube 10 to rise again. This action recurs in a fairly regular manner, causing the surface of the water in tube 10 to rise and fall alternately and to act as a liquid piston.

When the surface of the water falls in 105 tube 10 the check valve 15 will be pulled open, the valve 18 will drop shut and air will escape from pipe 13 into pipe 10. When the surface of the water in pipe 10 rises the check valve 15 will drop shut, thus 110

5 preventing the return of air into pipe 13, the check valve 18 will be pushed open and air will be forced out of pipe 10 to the atmosphere. This action is made continuous so long as the recurrent formation of steam 10 takes place in pipe 8. It causes a reduction of pressure or partial vacuum in the system, acting from the return end. Water of condensation returning from the system through pipe 13 enters pipe 11 and returns 15 to the boiler at the bottom thereof.

10 I have found in practice that a vacuum or a partial vacuum which is entirely sufficient to successfully operate a steam heating plant may be maintained by the arrangement just described. One of the important features of this arrangement is that it is 15 automatic.

15 I find in practice that when the temperature of the water in the boiler is considerably below the boiling point, if the draft is kept clear and the fire bright directly at the bottom of the U-tube the operation is most noticeable.

20 25 In cold weather when high temperatures are needed a heavy fire is maintained and the system works under pressure. The U-tube works at such times and by the suction it produces assists in the elimination of air 30 and reduces the pressure at the return end of the system. But its apparently maximum effect is produced when the water in the boiler is below the boiling point, or merely 35 vaporizing. At such times air meets with no resistance in entering the ordinary system and its elimination is most important so that the system may be filled with lower temperature vapor when a low temperature is desired. In other words, if the system is 40 economically designed, in very cold weather a certain amount of pressure is needed. The pressure at the boiler end and the suction of the U-tube pump at the other end promote the circulation of steam very efficiently 45 and the action of the pump eliminates the air. In moderately cold weather when no pressure is needed in the system, the action of the U-tube pump is most needed and it is under just such conditions that its action is most apparent.

50 While I have shown one form of the device, it is obvious that other forms might be used without departing from the spirit of the invention.

55 Thus the structure described in the foregoing specification and in the annexed claims going specifically with any steam heating system may be used with reduction of pressure or the in which the reduction in the system is necessary elimination of air 60 or desirable.

65 In further explanation of my improved process and apparatus two legs of a U-tube, the pipes 8 and 10 form the heated pipe 8, one leg of which, namely the end with an end 70

75 large receptacle, in the present illustration the steam dome 7. It is a well known fact that if water is contained in two vertical tubes connected at the top and bottom and opening at the top of one vertical leg or tube, a circulation of water will be started upon the application of heat to the open leg and this circulation will continue up the heated leg, across the top, down the unheated leg and across the bottom to the 80 heated leg. This is caused by the water in the heated leg expanding and thus becoming lighter. The more the water is heated the faster the circulating movement thereof, and when the water is heated to such an extent 85 that steam is formed, the mixed water and steam in the heated leg is still lighter and the circulating movement is greatly accelerated.

90 Should the connection at the tops of the two legs be removed and their upper ends separated as in the present instance, the mixed water and steam in the heated leg will flow upward and spread out within the receptacle at the top, namely the steam dome 7, 95 and the water in the unheated leg will flow down until most of the steam escapes from the heated leg, whereupon the weight of the column of water in the heated leg overcomes that of the lowered column in the unheated 100 leg and a reverse movement takes place as the water flows down the heated leg and up the unheated leg. Because of the proportionately greater area of the receptacle at the top of the heated leg as compared to that of the leg itself, the water naturally spreads out over this area and the length of the water column is not increased except to an extremely slight degree so that the formation of steam in the heated column and the escape of this steam from the water at the surface above the heated leg thus makes, for the moment, an unbalanced or differential weight or pressure with an immediate consequent shortening of the column of water 105 in the unheated leg to balance.

I claim:

110 1. The process of producing and maintaining a vacuum within a container by applying heat to one leg of a U-shaped tube connected to the container, to cause the rise and fall of a liquid contained in the tube, applying this force to draw air from the container and to discharge it into the atmosphere, and at the same time preventing 115 a reverse movement of the air.

120 2. The herein described process of maintaining a vacuum within a container which consists in applying heat to the water in one column of a U-shaped tube whose other column is connected to the container, thereby causing the level of the water in the latter column to rise and fall, allowing air in the container to take the place of the rarefied air 125 in the latter column when the level of the 130

liquid falls and discharging air in the latter column through a separate discharge opening, while at the same time preventing the re-entrance of air into the container.

- 5 3. In a device for maintaining a vacuum in a container, a boiler having a steam dome, a tube having connection with the bottom of the steam dome and being provided with a connecting arm extending above the steam dome, a container having communication with said connecting arm near the upper end thereof, a check valve for permitting the passage of air from the container into the connecting arm, but preventing the reverse flow 10 of the air, and a check valve carried by said connecting arm near the top thereof, for permitting the exit of air from the connecting arm and for preventing the entrance of air into the connecting arm from the outer 15 atmosphere.

- 20 4. In a device for maintaining a vacuum, a container pipe, a boiler, a U-shaped tube having a short arm communicating with the boiler below the level of the water, the 25 longer arm of said U-shaped tube projecting above the level of the liquid, said longer arm having near its upper end an outlet into the outer atmosphere and said container being connected with the longer arm of the 30 tube near said outlet, a check valve at the junction of the container with the long arm, for permitting the passage of air from the container into the long arm but for preventing a reverse flow of the air, and a check 35 valve carried by the long arm, for permitting the exit of air from the long arm into the outer atmosphere, but preventing the reverse flow.

- 40 5. The combination with a steam boiler, of a container, and means in connection with the boiler and actuated thereby during normal operation of the boiler for pumping a portion of the air out of the container, whereby to maintain a partial vacuum on 45 the container.

6. The combination with a steam boiler having a steam dome, of a container connect-

ed with the bottom of the boiler, means carried by the boiler for pumping a portion of the air out of the container, thereby maintaining a partial vacuum on the container, 50 said means comprising a U-shaped tube having a short arm and a long arm, the short arm of the tube being connected with the bottom of the steam dome beneath the level 55 of the water, and the long arm extending above the level of the water, a connection between the container and the long arm, means for permitting a flow of air from the container into the long arm and means for 60 permitting a flow of air from the long arm to the outer atmosphere while preventing a reverse flow.

7. The process of producing and maintaining a vacuum in a container by intermittently withdrawing air from the container through the force of the alternate rise and fall of a fluid in a U-shaped tube having heat applied at or near the base of one vertical leg.

70 8. An apparatus comprising a U-shaped tube adapted to contain a liquid, means for heating one arm of the U-shaped tube, for causing fluctuation of the level of the liquid in the arms of the tube, and a valve connected with the other arm of the tube for permitting the discharge of air from the tube and for preventing the returning of air, thus discharged to the tube.

75 9. An apparatus comprising a U-shaped tube adapted to contain a liquid, means for heating one arm of the U-shaped tube to cause fluctuation of the level of the liquid in the other arm of the tube, a container, a connection between the container and the 80 last mentioned arm of the tube, and means for permitting the flow of air from the container into the last mentioned arm of the tube and from the latter to the atmosphere, while preventing a reverse flow.

THOMAS TIBBETS.
